GESELLSCHAFT, OF ESSEN-ON-THE-RUHR, GERMANY.

PROJECTILE.

932,214.

Specification of Letters Patent. Patented Aug. 24, 1909.

Application filed October 29, 1908. Serial No. 460,131.

To all whom it may concern:

Be it known that I, KARL WIESER, a subject of the Emperor of Germany, and a resident of Bredeney-on-the-Ruhr, Germany, have invented certain new and useful Improvements in Projectiles, of which the following is a specification.

The present invention relates to the type of projectiles (exploding, illuminating, incendiary and the like projectiles) which is provided with a shaft serving for guiding the projectile in the projecting device (the gun barrel for instance). This shaft is for instance necessary when the projectile body proper, which for instance contains the bursting charge, is of greater caliber than the gun barrel serving for throwing the projectile. In the known projectiles of this type the shaft is rigidly connected with the projectile and the shaft and projectile therefore remain connected together throughout the entire path of flight. Due to this fact the shaft has a detrimental effect on the path of flight of the projectile, as has been demonstrated by trials, the shaft causing the projectile to tilt and, in case of strong lateral wind, causing the projectile to become deflected to a considerable extent from its direction of flight. In accordance with the present invention these drawbacks are avoided by having the shaft connected with the projectile-body so as to be readily detached therefrom and in such a manner that the shaft can separate from the projectile body soon after the projectile has commenced its movement.

As an example of the invention the accompanying drawings show an exploding projectile which is to be thrown by a gun. Figure 1 shows the projectile partly in elevation and partly in section, part of the gun barrel being shown, and Fig. 2 is a section on line 2—2, Fig. 1, looking from the right.

The projectile has a thin-walled body A which contains a charge B of high-explosive material. The body A is of spherical form and its diameter is considerably greater than the caliber of the gun barrel C and shaft D. A sleeve E which is composed of two parts is arranged diametrically in the body A. The sleeve is secured to the body A by means of two flanges e¹ e²; the sleeve contains a fuse F—preferably a time-fuse—and a detonator G and serves for connecting the

shaft D with the projectile-body. The shaft is composed of three cylindrical parts of different diameter. That part (d¹) of the shaft which is of smallest diameter is loosely inserted in the sleeve E and in a cap H which is secured to the flange e² of the sleeve E. The cap lies with a spherical surface against the flange e² and serves for transmitting to the projectile-body A the pressure which acts on the shaft D when the gun is fired. To that end the shaft abuts with a shoulder d³ against the cap H. The shoulder is produced by the change in diameter between the shaft-part d¹ and the longer shaft-part which is of intermediate diameter. The latter shaft-part is provided with ribs d⁴ which together with the shaft-part d², the diameter of which corresponds to the caliber of the smooth barrel, serves for guiding the shaft in the gun barrel.

On the shaft D is loosely and slidably mounted a disk-shaped weight K which serves for separating the shaft from the projectile-body after the gun is fired. The weight K is provided with a bore which corresponds to the diameter of the part of the shaft which carries the ribs d⁴. The weight is further provided with grooves k¹ for the ribs d⁴. The ring-sector shaped ribs k² (Fig. 2) located between the grooves k¹ on the weight form a stop for the shaft-part d².

The drawings show the position which the several parts of the projectile assume before the gun is fired. When the gun is fired the shaft D is ejected from the gun barrel and carries the projectile-body A along, while the weight K, which is loosely slidable on the shaft, first remains behind relatively to the shaft due to the inertia of the weight. When the ribs k² of the weight hit the shaft-part d² the velocity of the shaft becomes less than the velocity of the projectile-body and the projectile-body therefore separates from the shaft soon after the gun is fired, the projectile-body then proceeding farther alone in the direction of flight imparted thereto by the shaft.

The invention can also be directly applied to incendiary projectiles, illuminating projectiles and the like and also to such projectiles which are ejected by means of springs, compressed air and the like. The weight K might also be replaced by stops arranged at the muzzle of the gun barrel and cooperating with stops provided near the free end (d²) of

the shaft. These stops would have to be constructed in such a manner as to permit the shaft passing out of the gun barrel while on the other hand they would have to coöperate to retard the movement of the shaft in such a manner that the shaft would separate from the projectile-body soon after the beginning of the movement of the projectile.

Having thus described the invention what is claimed and desired to be secured by Letters Patent is:—

1. A projectile having a projectile-body, a shaft for guiding the projectile in the projecting device, said shaft having driving and non-restraining connection with the projecting device, and a connection between the projectile-body and the shaft permitting said parts to separate at substantially upon the beginning of flight thereof.
2. A projectile having a projectile-body, a shaft for guiding the projectile in the projecting device, said shaft having driving and non-restraining connection with the projecting device, and removably connected with the projectile-body, and means causing the shaft to separate from the projectile-body upon the beginning of flight thereof.
3. A projectile having a projectile-body, a shaft for guiding the projectile in the projecting device and removably connected with the projectile-body, and means causing the shaft to separate from the projectile-body after firing, said means comprising a weight mounted to slide loosely on the shaft,

and a stop on the shaft adapted to be engaged by the weight to retard the movement of the shaft.

4. A projectile having a projectile-body, a cap on said body, and a shaft for guiding the projectile in the projecting device and having a shoulder-abutting said cap.

5. A projectile having a projectile body, a sleeve in said body, a shaft within said sleeve for guiding the projectile in the projecting device, said shaft having driving and non-restraining connection with said projecting device, and means carried by said shaft for separating the projectile therefrom during the flight thereof.

6. A projectile having a projectile-body, a sleeve in said body, a fuse in said sleeve, and a shaft for guiding the projectile in the guiding device and loosely inserted in said sleeve.

7. A projectile having a projectile-body, a shaft for guiding the projectile in the projecting device and removably connected with the projectile-body, and means carried by said shaft for positively effecting separation of said shaft and the projectile-body during the flight thereof.

The foregoing specification signed at Bar-
men, Germany, this 15th day of September,
1908.

KARL WIESER. [L. s.]
